RETRIEVER

George J. Dawn, Waukegan, Ill.

Application July 20, 1937, Serial No. 154,646

5 Claims. (Cl. 294—19)

This invention relates to a retriever which in one embodiment of the invention may be employed as a retriever for recovering a golf ball from water hazards, ditches, or any place out of 5 normal reach of a person.

One object of the invention is to provide a device of this character including an elongated handle carrying a stationary member at its outer or front end and a rotary shaft journaled through 10 the handle and having actuating means at its rear end for turning the shaft and at its front end provided with a member movable towards and away from the stationary member when the shaft is turned in the proper direction. It will 15 thus be seen that the device may be held by its handle and rotary motion imparted to the shaft so that a golf ball may be gripped between the stationary member and the movable member or a closure carried by the movable member 20 moved into closing relation to a net carried by the stationary member.

Another object of the invention is to so form the handle and the rotary shaft journaled through the handle that sections having telescoping engagement with each other may be slid 25 longitudinally and thus reduce the handle and the shaft to such a length that the device may be easily carried in a golf bag or in a person's hand and be extended longitudinally to any desired length in its limits during use if found 30 necessary.

Another object of the invention is to provide a device of this character which is of a simple construction, very easy to operate and not liable 35 to get out of order.

The invention is illustrated in the accompanying drawings, wherein

Figure 1 is a perspective view of a golf ball retriever constructed in accordance with this 40 invention,

Figure 2 is a sectional view taken longitudinally through the handle and rotary shaft,

Figure 3 is a sectional view taken transversely 45 through the handle and the shaft along the line 3—3 of Figure 2,

Figure 4 is a fragmentary view of the forward end portion of the device and illustrating a modified construction,

Figure 5 is a fragmentary view illustrating a 50 modified formation of the forward end portion of the rear section of the handle,

Figure 6 is a view illustrating another modified form of forward end portion for the rear handle 55 section,

Figure 7 is a sectional view taken longitudinally through a modified form of retriever,

Figure 8 is a view looking down upon a portion of Figure 7, and

Figure 9 is a sectional view taken transversely 5 through Figure 7 upon the line 9—9.

This improved retrieving device is provided with a handle 1 consisting of a forward section 2 and a rear section 3. All of the sections are formed of tubing which may be made of metal or 10 any suitable material and may be round, hexagonal, square or any other desired regular or irregular shape in cross section and of any desired length and diameter, provided the relative diameters of the two sections are such that the 15 forward sections may be slidably received in the rear sections and thus the two sections have telescopic engagement with each other. The forward extremity of the rear handle section is crimped inwardly, as shown at 4 in Figures 1 20 and 2, and slit longitudinally, as shown at 5, so that the forward end portion of the rear handle section, which is formed of resilient metal, will have binding engagement with the forward section. If so desired, the rear section may be 25 formed of metal or any suitable material which is not necessarily resilient, in which case a split ring 6 of resilient metal or other suitable material will be engaged about the forward end of the rear handle section in the external circumfer- 30 entially extending feet defined by the crimped portion 4 and cause a good binding engagement between the rear handle section and the forward handle section. Such a construction is illus- 35 trated in Figure 5, and in Figure 6 there has been shown another modified construction where- in the forward end portion of the rear handle section is split longitudinally, as shown at 7, and is externally tapered and threaded, as shown at 8, in order that a clamping ring 9 may be 40 screwed upon the forward end portion of the rear handle section to draw this split forward end portion into tight binding engagement with the forward handle section.

A rod or actuating shaft extends longitudinally 45 through the tubular handle, and upon referring to Figure 2, it will be seen that this shaft consists of a front section 10 and a rear section 11, the rear section being of tubular formation and having telescoping engagement with the front 50 section which is preferably solid but may be tubular if so desired. The forward portion of the front section 10 projects outwardly through the front end of the forward handle section 2 and is bent laterally to form a jaw 12 which is arcuate longi- 55

tudinally, as shown clearly in Figure 3, in order that it may engage about a golf ball, as shown in Figure 1. This jaw 12 cooperates with the jaws 13 which project laterally from a cross-head 14 extending longitudinally of the forward handle section and welded or otherwise firmly secured thereto, as shown at 15, and since the jaws 13 are disposed in planes at opposite sides of the jaw 12 and are also arcuate longitudinally, as shown clearly in Figures 1 and 3, a golf ball 16 may be very firmly gripped between the jaws or claws when the jaw 12 is swung toward the jaws 13. End portions of the forward handle section 2 are bent inwardly to provide a circumferentially extending abutment flange 17 for engagement by a ring 18 seated in a circumferentially extending groove 19 formed in the forward portion of the front shaft section 10, and it will be readily understood that, when the front shaft section is thrust into the handle and the forward portion of the handle section 2 then rolled inwardly to form the flange 17, longitudinal movement of the shaft section 10 will be limited and the jaw or core 12 cannot move out of its proper relation to the jaws 13. The tubular rear shaft section 11 fits snugly about the forward shaft section but is loosely received in the rear portion of the forward handle section 2, and referring to Figure 2, it will be seen that the rear end of the forward handle section is crimped, as shown at 20, to provide a circumferentially extending external seat into which fits an inwardly extending rib formed by crimping the rear handle section inwardly, as shown at 21. By this arrangement rearward sliding of the rear handle section along the forward handle section will be halted when the rear handle section reaches the position shown in Figures 1 and 2. The rear end portion of the rear shaft section 11 carries a pin 22 which passes transversely through it and serves to limit rearward sliding of the rear shaft section through the rear handle section by engagement with the inturned circumferentially extending flange 23 and the portion of the rear shaft section which projects from the rear end of the rear handle section laterally to provide a turning member 24. By so mounting the rear shaft section it may slide longitudinally with the rear handle section, and in view of the fact that the rear shaft section and the forward shaft section have frictional engagement with each other, the forward shaft section will be turned with the rear shaft section when the turning member 24 is grasped and movement imparted thereto in a direction to rotate the shaft and move the jaw 12 toward or away from the two jaws 13. It will thus be seen that, when the retriever is in use, it may be extended to any desired length in its limit by drawing the rear handle section rearwardly of the front handle section and the hand-hold 25 then grasped with one hand and the retriever extended toward a golf ball in a ditch, water hazard or remote place. It is then merely necessary to impart turning movement to the shaft and the jaw 12 will be moved toward the jaw 13 to grip the ball. After the golf ball has been gripped between the jaws, it is merely necessary to draw the retriever towards the person using the same and then actuate the turning member 24 to move the jaw 12 away from the jaws 13 and the ball will be released. The rear handle section and the rear shaft section may then be thrust forwardly to a retracted position and the retrieving device will be shortened to such an extent that it can be easily placed in a golf bag. Instead of welding or otherwise firmly securing the cross-head 14 to the

front end of the forward handle section, it may be provided with a socket 26, as shown in Figure 4, which is firmly secured under the cross-head in any desired manner and is internally threaded in order that it may be screwed upon the forward end portion of the forward handle section. While the handle has been shown formed of two sections, it is obvious that it may be formed of three, four or any desired number of sections. By placing soft rubber tubing about the jaws 12 and 13, the device may be used for picking fruit without bruising the fruit.

In Figures 7, 8 and 9, there has been illustrated a retriever of the type illustrated in Figures 1 through 6 but of a modified construction. In this embodiment of the invention, there has been shown a handle formed of a front section 32, a rear section 33 and an intermediate section 34. These sections are of tubular formation, as shown in Figures 7 and 9, and may be of any length and diameter desired. While they have been shown formed with six faces in Figure 9, it is to be understood that they may be of any cross sectional outline desired. It will also be understood that, while the handle has been shown formed of three sections, any number may be provided. The forward end portion of the intermediate section is slit longitudinally from its front end to provide latches 35 located at opposite sides of the handle section and the forward end portion of each of these latches is bent inwardly, as shown in Figure 7, to provide the latch with a bill 36 adapted to engage in a seat 37 formed in the front handle section 32 when the front handle section is drawn outwardly and thus prevent the front handle section from being drawn outwardly beyond a desired extent. When, however, it is desired to intentionally entirely withdraw the front handle section from the intermediate handle section, the free ends of the latches may be sprung outwardly and the front handle section entirely withdrawn. While two latches have been shown located diametrically opposite each other, it is to be understood that one or any other number desired may be provided. In view of the fact that the handle sections have flat faces, they will be prevented from turning relative to each other and the latches will, therefore, always be in the proper position for entering the seats 37 and limiting outward movement of the front handle section from the intermediate section. Movement of the intermediate section should also be limited as it is drawn outwardly from the rear handle section and thus prevent accidental entire withdrawal of the intermediate section. In order to do so, tongues 38 have been struck from certain of the flat faces of the rear handle section and curved longitudinally so that they protrude inwardly for engagement in slots 39 formed in corresponding faces of the intermediate section in spaced relation to the rear end thereof. By so forming the tongues or latches 38, their free rear ends may have abutting engagement with the intermediate handle section at rear ends of the slot 39 to limit outward longitudinal movement of the intermediate section but, when the intermediate section is moved rearwardly into the rear section, the curved latching tongues will be flexed outwardly through the slot 40 of the rear section and rearward movement of the intermediate section will not be interfered with. It will thus be seen that the intermediate section as well as the front section of the handle may be freely moved rear-

wardly to a retracted position but forward or outward movement of the intermediate section will be limited. When it is desired to entirely remove the intermediate section from the rear section, it is merely necessary to spring the free rear ends of the latching tongues outwardly by a pin or the like inserted through the slot 40 and the intermediate section may then be entirely withdrawn. Inwardly extending annular guide flanges 41, 42 and 43 are formed at rear ends of the handle sections 32, 33 and 34 which define circular openings, as shown in Figure 11, and at its front end the forward handle section is also formed with an annular guide flange 44 defining a circular opening. A hand-hold 45, corresponding to the hand-hold 25, is mounted upon the rear handle section and at its front end the front handle section carries a cross-head 46 and jaws 47, corresponding to the jaws 13 and cross-head 14. A shield 48 of soft rubber is fitted upon each of the jaws 47 so that this device may be employed for removing fruit from trees without bruising the fruit. It is to be understood that the soft rubber sleeves may be omitted when the device is to be used for retrieving golf balls and the like.

The actuating shaft, which corresponds to the actuating shaft shown in Figure 2, consists of a forward section 49 which is preferably of solid metal or other desired material, and an intermediate section 50 and rear section 51, both of which are of tubular formation. The shaft sections correspond in cross sectional outline to the sections of the handle but need not necessarily be of this particular cross sectional outline. In view of the fact that the actuating shaft is to be turned in the handle, the opening defined by the flanges of the handle section must be circular, as shown in Figure 9. The diameter of the opening defined by each of the flanges is such that, while it permits the shaft section to turn, the marginal edge of the flange will have contacting engagement with the shaft section and the shaft will be maintained in concentric relation to the handle and sliding movement of the shaft section guided. A ring 52, corresponding to the ring 18 and mounted in a circumferentially extending groove 53 formed in the forward shaft section, is provided to engage the front flange 44 and limit forward sliding movement of the front shaft section relative to the front handle section. There has also been provided a pin 54, corresponding to the pin 22, secured through the rear shaft section in position to engage the rear flange 42 and limit rearward longitudinal movement of the rear shaft section relative to the rear handle section. The intermediate shaft section is provided at its front end with latches 55 which are of the same construction as the latches 35 of the intermediate handle section and terminate in bills 56 for engaging in the recesses or seats 57 formed in the forward shaft section. It will thus be seen that forward longitudinal movement of the front shaft section will be limited in the same manner in which forward movement of the front handle section is controlled. Latching tongues 58, which correspond to the latching tongues 38, are cut from forward end portions of the rear shaft section for engaging in slots 59 formed in the rear portion of the intermediate shaft section and limiting forward movement of the intermediate section 50 out of the rear shaft section 51. The protruding rear end portion of the rear shaft section is bent laterally to provide a turning member 60, corresponding to the turn-

ing member 24, and the protruding forward end portion of the front shaft section is bent to form a jaw 61, corresponding to the jaw 12, for cooperating with the jaws 47. This jaw 61 is also covered by a shield 62 of soft rubber tubing 5 when the device is used for picking fruit but the protecting tube will be omitted when the device is to be used for retrieving golf balls and the like.

Having thus described the invention, what is 10 claimed as new is:

1. A device of the character described comprising a tubular handle formed of companion sections, the said sections being in telescoping engagement with each other, a shaft extending 15 longitudinally through said handle and having companion sections in telescoping engagement with each other and with the forward portion of a section of the shaft fitting snugly about the rear portion of a section in front of the same in 20 frictionally gripping engagement therewith, the rear end of the rear section being projected from the rear end of the rear handle section and bent to form a turning member, the front end of the forward shaft section being projected forwardly 25 from the front handle section and bent to provide a movable member extending laterally of the shaft and handle, and a stationary member carried by the front end of the forward handle section 30 in cooperating relation to the movable member.

2. A device of the character described comprising a tubular handle consisting of front and rear sections in telescoping engagement with each other, the forward end of the rear handle section 35 being slit longitudinally, a binding member about the slit forward end of the rear handle member contracting the same to create frictional binding between the handle sections, portions of the front and rear handle sections being crimped to form 40 a circumferentially extending seat and a circumferentially extending rib for engaging in the seat and holding rearward sliding movement of the rear handle section along the front handle section, a shaft extending through said handle and 45 consisting of front and rear sections in telescoping engagement with each other, means for preventing sliding of the shaft sections out of the handle section, a stationary member carried by the front handle section and extending laterally 50 therefrom, the forward portion of the forward shaft section being extended out of the handle and bent to form a laterally extending movable member in cooperatitng relation to the stationary member, and the rear end portion of the rear 55 shaft section being extended out of the handle and bent to form a turning member.

3. A device of the character described comprising a tubular handle of telescoping sections, a shaft of telescoping sections extending longitudinally through the handle and rotatable therein, an outer one of a companion pair of telescoping sections being formed with a resilient latching strip and the companion inner telescoping section being formed with a seat to receive a portion of the resilient latch and limit longitudinal 60 sliding movement of the inner telescoping section out of the outer telescoping section, and means for imparting turning movement to said shaft.

4. A device of the character described comprising a tubular handle of telescoping sections, a shaft of telescoping sections extending longitudinally through the handle and rotatable therein, the rear section of said shaft being provided with turning means, an outer one of a companion 70

pair of telescoping sections being slit from its front end to provide a resilient latching tongue having its front end bent inwardly to provide a bill, and the inner one of the companion telescoping sections being formed with a seat to receive the bill and limit forward movement of the inner telescoping section out of the outer telescoping section.

5. A device of the character described comprising a tubular handle of telescoping sections, a shaft of telescoping sections extending longitudinally

nally through the handle and rotatable therein, the rear section of said shaft being provided with turning means, an outer one of a companion pair of telescoping sections having a tongue cut therefrom and curved longitudinally to provide an inwardly extending latch, and the inner end of the companion telescoping sections being formed with a slot to receive and limit longitudinal movement of the outer telescoping section.
